PLLC(57) **CLAIM**

The ornamental design for a door channel, as shown and described.

DESCRIPTION

FIG. 1 is a front, left and bottom perspective view of a door channel showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a perspective view thereof shown in an alternate position;

FIG. 9 is a front, right and bottom perspective view of a second embodiment;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9; and,

FIG. 16 is a perspective view of FIG. 9 shown in an alternate position.

The broken lines shown represent unclaimed subject matter of the door channel and form no part of the claimed design. The dash-dot lines represent the boundary between the claimed design and unclaimed design.
